(57) **CLAIM**

The ornamental design for a spray cap, as shown and described.

DESCRIPTION

FIG. 1 is a perspective view of a spray cap in accordance with the present design with the cap body and a container shown in broken line;

FIG. 2 is a rear view thereof;

FIG. 3 is a right side view thereof;

FIG. 4 is a left side view thereof; and,

FIG. 5 is a top view thereof.

The broken lines are shown for the purpose of illustrating both parts of the article as well as environmental subject matter. None of the broken lines form part of the claimed design.

1 Claim, 5 Drawing Sheets
